UNITED STATES PATENT OFFICE

HARRY FRANCIS WEAVER, OF EVANSVILLE, INDIANA

DESIGN FOR A WATER-CLOSET-TANK COVER

Application filed October 30, 1930. Serial No. 37,437. Term of patent 14 years.

To all whom it may concern:

Be it known that I, HARRY F. WEAVER, a citizen of the United States, residing at Evansville, in the county of Vanderburg and State of Indiana, have invented a new, original, and ornamental Design for Water-Closet-Tank Covers, of which the following is a specification, reference being had to the accompanying drawing, forming part thereof.

Fig. 2 is a top plan view of the cover.

I claim:

The ornamental design for a water closet tank cover, as shown.

HARRY FRANCIS WEAVER.
